Fig. 3

Fig. 5

Fig. 4

Fig. 6

Fig. 7

Fig. 8

FIGURE 1 is a front elevational view of a dispenser top for a pressurized can, showing my new design;

FIG. 2 is a side elevational view of the dispenser top for a pressurized can;

FIG. 3 is a rear elevational view of the dispenser top for a pressurized can;

FIG. 4 is a top plan view of the dispenser top for a pressurized can;

FIG. 5 is a bottom plan view of the dispenser top for a pressurized can;

FIG. 6 is a front perspective view of the dispenser top for a pressurized can;

FIG. 7 is a rear perspective view of the dispenser top for a pressurized can; and

FIG. 8 is a longitudinal section taken through the dispenser top.

The dominant features of my design reside in the portions shown in full lines.

I claim:

The ornamental design for a dispenser top for a pressurized can, as shown and described.
